(57) **CLAIM**

The ornamental design for a key configuration for a handset, as shown and described.

DESCRIPTION

FIG. 1 is a perspective front view of a key configuration for a handset showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken line showing of environmental structures is for illustrative purposes only and forms no part of the claimed design.
